UNITED STATES PATENT OFFICE.

WILLIAM L. CASPER, OF BROOKLYN, NEW YORK, ASSIGNOR TO WESTERN ELECTRIC COMPANY, INCORPORATED, OF NEW YORK, N. Y., A CORPORATION OF NEW YORK.

REPEATING COIL.

Application filed June 11, 1921. Serial No. 476,676.

This invention relates to transmission circuits and pertains more especially to a speech transmission circuit in which there is provided an input transformer for a vacuum tube repeater, the cathode of which is grounded, as is usual in telephonic circuits.

The transformers usually employed in such circuits are composed of multi-layer coaxial coils which are so arranged that the capacities between the coils and the core or between the coils and the casing are practically negligible, whereas the capacities between the adjacent layers of the superposed coils have considerably larger values which can not be neglected.

It is the object of this invention to materially reduce in such a circuit the effect of the capacity between the primary and secondary windings of the transformer. This object is accomplished by connecting the grid of the associated vacuum tube to a layer of the secondary non-adjacent to the primary and the grounded cathode of the tube to a layer of the secondary adjacent the primary.

The invention will be better understood by having reference to the following specification and accompanying drawing wherein Fig. 1 discloses the winding of the transformer and its connections and Fig. 2 is a diagrammatic representation thereof.

In one embodiment, the transformer comprises a substantially rectangular frame 1 around the ends 2 and 3 of which are wound the multi-layer primary coils 4 and 5. Surrounding the coils 4 and 5 and having their inner layers adjacent the outer layers of said coils are the multi-layer secondary coils 6 and 7 which cooperate with the coils 4 and 5 to form the primary and secondary of the transformer. Binding posts 8, 9, 10 and 11 are provided for the inner and outer layers of the primary coils 4 and 5. The inner and outer layers of the secondary coils 6 and 7 are provided with the binding posts 12, 13, 14 and 15. The binding posts 8 and 11 are connected to the incoming line and a conductor 16 connects the binding posts 9 and 10. The conductor 16, by virtue of its symmetrical position with respect to the incoming line of the circuit is maintained at effective ground potential because of the capacities to ground of the two members of the incoming line. The binding posts 13 and 14 of

the secondary coils are connected by a conductor 18, the binding post 12 with the grid 19 of a vacuum tube 20 and the binding post 15 with the cathode 21 of said tube, said connection being grounded at 22. The anode 23 and the cathode 21 of the tube are connected with the output side of the circuit in the usual way.

Fig. 2 discloses diagrammatically the effect of this method of connection upon the capacities between the adjacent layers of the primary and secondary coils. Those portions of the coils adjacent the binding posts 8, 10, 12 and 14 represent the outer layers of the coils 4, 5, 6 and 7, respectively, and those portions adjacent the binding posts 9, 11, 13 and 15 represent the inner layers of said coils 4, 5, 6 and 7, respectively. The capacities A and B are, therefore, conveniently represented as being between the outer end of coil 4 and the inner end of coil 6 and between the outer end of coil 5 and the inner end of coil 7 respectively. The ratio of the impedance of the primary coil 4, in a commercial embodiment of this invention, to that of the secondary is approximately one to a thousand, and therefore the primary coil 4 may, for all practical purposes, be considered merely as a plate. The capacity A consequently has practically the same effect as if it were between the inner end of coil 6 and the member 16 of ground potential and is, due to the ground connection 22, in effect shunted around the coil 7. Since the terminals 10 and 15 of the capacity B are connected to ground potential member 16 and to the ground 22 respectively, the effect thereof is nullified. The single effective capacity A can shunt out only a very small portion of the incoming potentials of the higher frequencies and the circuit is therefore capable of high quality speech transmission.

Although the transformer sections are disclosed as being wound around the ends of a rectangular frame, this construction being known as core type, it is to be understood that they may be arranged upon a central limb of the core in axial alinement, which construction is known as shell type. Furthermore, although each of the primary and secondary windings are here disclosed as comprising a pair of sections, it is within

the spirit of this invention to compose either of said windings of a single section or of several sections.

What is claimed is:

5. 1. In combination in an electrical system, an electric device having a normally grounded element, a line, and a transformer for connecting said line to said device, said transformer having superposed primary and 10 secondary windings, the primary winding being connected to said line, said secondary winding comprising a plurality of superposed layers, the layer thereof adjacent said primary winding being connected to the 15 grounded element of said electric device.
2. The combination, as claimed in claim 1, in which said electric device comprises a space discharge device having a grounded cathode, and a grid, the layer of said secondary winding which is non-adjacent said primary winding being connected to said grid.
3. A transmission circuit comprising an incoming line having its two sides balanced 25 with respect to ground, a vacuum tube repeater having a cathode, a grid and an anode, a transformer for connecting said line to the input of said vacuum tube, said transformer comprising sections each 30 consisting of primary and secondary windings, the windings within each section being in superposed layers and connections between the sections of the respective windings and from the winding terminals to said line and 35 said vacuum tube, respectively, such that in each section of the secondary winding the circuit leading from the grid passes first to the layer most remote from the primary winding while the circuit leading from the cathode passes first to the layer adjacent the 40 primary winding, and a connection from said cathode to ground.
4. The method of reducing the effective shunt capacity of a step-up transformer for 45 the input circuit of a vacuum tube repeater, comprising disposing the secondary winding in a plurality of sections connected in series with one another whereby the turn-to-turn shunt capacity of the secondary winding is reduced, and reducing the shunt-

ing effect of the capacity between windings by connecting the grid and cathode leads so that the lead from the grid passes first to the layer in each section of the secondary winding that is most remote from the primary while the lead from the cathode passes first to the layer of the secondary, in each section, that is adjacent the primary.

5. A transmission circuit comprising a line balanced with respect to ground, a 55 vacuum tube having a grid and a grounded cathode, and a transformer having a primary winding connected to said line and a secondary winding connected to said cathode and grid, said secondary winding comprising a plurality of multi-layer winding sections, the primary winding and the layers within each section of said secondary winding being in superposed relation, a connection from the end of each secondary section 60 winding most remote from the primary to the end of the next secondary sectional winding adjacent the primary winding, a connection from the secondary winding terminal most remote from the primary winding to the grid, and a connection from the secondary winding terminal adjacent said primary winding to said cathode.

6. In a transmission circuit, an incoming line having its terminals substantially balanced with respect to ground, a transformer having a pair of multi-layer primary windings, a connection from the outer layer of one of said windings to one terminal of the other of said windings, connections between the other terminals of said windings and the terminals of said line, a pair of multilayer secondary windings for said transformer surrounding said primary windings, a vacuum tube having a cathode and a 65 grid, a connection from the inner layer of the secondary winding surrounding the first mentioned primary and the cathode of the tube, a connection from the outer layer of the other secondary winding to the grid of the 70 tube, and a connection from the cathode of the tube to ground.

In witness whereof, I hereunto subscribe my name this 10th day of June A. D., 1921.

WILLIAM L. CASPER.
